UNITED STATES PATENT OFFICE.

GALELMA BUTCHER, OF NORFOLK, VIRGINIA.

WINDOW ADJUSTMENT.

Application filed January 4, 1926. Serial No. 79,221.

This invention relates to improvements in window constructions.

The primary object of this invention is the provision of an improved window construction, embodying a relatively simple type of movable stop bead construction which will permit of the facile detachment of the window sashes from the frame.

A further object of this invention is the provision of an improved adjustable stop and parting bead or strip construction for window constructions, embodying a novel movable assemblage in its relation to a window casing, to permit the easy detachment of the sash or sashes thereof.

A further object of this invention is the provision of an improved retaining strip construction for windows including a movable retaining strip portion having both stop bead and parting bead portions formed thereon, and for novel movable assemblage with the pulley box or stile of the window casing.

A further object of this invention is the provision of an improved window construction embodying an adjustable strip for the window casing or frame, preferably detachable with respect to a window casing to permit of the detachment and removal of sashes, and which embodies a relatively compact and durable construction which may be very securely attached to the window casing, and which may be easily detached therefrom.

Other objects and advantages of this invention will be apparent during the course of the following detailed description.

In the accompanying drawings, forming a part of this specification, and wherein similar reference characters designate corresponding parts throughout the several views,

Figure 1 is an inside view of a window construction, showing the sashes thereof closed, with certain novel retaining strip features to hold the sashes in place, and which retaining strip features are movable to permit the easy detachment of the sashes from the window construction.

Figure 2 is a vertical sectional view taken thru the window construction, showing certain novel details.

Figure 3 is a fragmentary perspective view of the retaining strip structure of the window construction, showing the novel

movable feature thereof for permitting the sashes to be swung into easily accessible and removable position.

Figure 4 is a perspective view of a novel type of retaining strip embodying both parting bead and stop bead in a definite and integral relation.

Figure 5 is a movable portion of a retaining strip construction for the window, embodying the principle of the retaining strip illustrated in Figure 4, but differing therefrom in that it is adaptable for use upon present window constructions, and includes means for connecting a conventional parting strip and stop bead in a definite and novel relation.

Figure 6 is a sectional view taken thru the retaining strip as illustrated in Figure 4, showing its association upon a weight box or stile of a window construction, with a sash assembled therein.

Figure 7 is a cross sectional view similar to the section illustrated in Figure 6, but one which utilizes the retaining strip construction as shown in Figure 5.

In the drawings, wherein for the purpose of illustration are shown preferred and modified forms of the invention, the letter A may generally designate the window construction, which may comprise a casing B within which upper and lower sashes C and D are slidably mounted, and retained therein by means of novel retaining strip constructions F and G at the side stiles of the casing B.

The principle of this invention, by means of which sashes may be opened for accessibility or removal may be applied to any form of window construction, such as the casement type, multiple sash type, or other window construction.

As illustrated in the drawings, the casing B may comprise the base sill 10, upon which the inside stool 11 rests. The weight boxes or casings each preferably includes a pulley stile 12; the inner and outer linings 13 and 14 respectively; and the back lining 15, all connected in such relation as to provide the weight compartment 16, within which the sash weights reciprocate; the linings and stile being connected in a suitable relation and attached to the sill and stool as desired. The window casing at the top thereof includes the head casing construction 18 of any

approved construction suitable for supporting the retaining strips in conventional relation.

The sashes C and D are of the conventional construction, each including the frame 20 supporting therein the transparent or translucent panes 21. The sashes C and D along the sides of the frames thereof are preferably detachably connected and supported by means of flexible pulley cables 25, which are trained over suitable pulleys 26 in upper openings in the pulley stile 12, in accordance with conventional construction; the inner ends of the cables 25 supporting weights which depend in the weight box compartment 16. The pulley stiles 12 in the lower portion thereof are provided with openings 28 as means of access to the compartments 16; the weights during an elevated position of the sashes being located adjacent the openings 18, in order to attach said weights. Normally the opening 28 is entirely closed by means of the removable portions H of the sash retaining strip constructions F and G, as will be subsequently described.

Referring to the retaining means for holding the sashes in place, the head casing 18 may be formed with a conventional bead or strip construction, and the conventional outer side stop beads or strips 30 may be connected along the side pulley stiles of the weight boxes, and form the means to retain the upper sash in sliding position 35 against removal from the outside of the window construction.

The retaining means F and G along each of the weight boxes includes the upper construction K formed rigid and fixed with the 40 weight box and pulley stile, and the lower movable portion H.

In so far as the upper fixed construction K at each side of the window casing is concerned, the same preferably includes a parting bead or strip 40, and an inner stop bead or strip 41, the same being connected in a spaced relation to provide a channel 42 along which the lower sash slides when the same is elevated. The parting strip or bead 40 is of course spaced with respect to the outer stop or bead 30, in order to provide a channel 42 for accommodation of the sliding sash C. In the preferred construction the parting strip 40 and the stop bead or strip 41 are connected rigid by means of a backing piece 45 which is attached to the pulley stile.

The movable sash retainer H which forms the lower portion for each of the side retaining constructions of the window sashes, 60 is formed to be movable away from the pulley stile or weight box, in order to permit removal of the sashes C and D, and each of the lower movable retaining portions H includes a portion of the stop bead 65 and a portion of the parting bead, rigidly

connected in spaced relation, either integral or otherwise.

As illustrated in Figure 4 of the drawings, the movable sash retaining strip H includes the back or body piece 50, on the forward 70 surface of which is formed the parting bead or strip 51 and the inner stop bead or strip 52 which is spaced from the bead 51 to provide a channel or groove 53 within which the frame of the lower sash D operates. In this construction it is to be noted that the retaining strip H is of one piece formation, all of the parts being integrally connected or formed of wood or metal, or other material. At the lower end of the retaining strip 80 H the parting bead 51 is stepped below the lower edge of the stop bead 52, in order that the same may respectively rest upon the offset top surfaces of the sill 10 and stool 11. Depending below and fixed in the parting bead 51 and the stop bead 52 are retaining shanks 55 and 56 respectively, which are adapted to be detachably received in suitable socket openings provided inwardly of the top surfaces of the sill 10 and stool 11 in order that the lower ends of each retaining construction H may be anchored to the sill structure of the window casing.

At the lower end of the fixed retaining strip construction K and at the top of the movable retaining strip construction H, the abutting edges of the same are somewhat novelly formed to permit the movement of the movable retainer H away from the window casing, inwardly of the room, at right angles to the plane of sashes; the abutting edges of the fixed and movable retaining constructions K and H being beveled to prevent movement of the movable retaining strip construction H inwardly of the opening 95 of the window casing, in the plane parallel with the sashes. To this end, as is illustrated in Figure 1 of the drawings, the lower edge of the fixed retainer K and the upper edge of the movable retainer H bevel 100 at an inclination to the vertical, sloping downwardly from the outer surface of the pulley stile 12 in the direction of the window casing opening, as illustrated at 58 in Figure 1 of the drawings. The abutting edges of the fixed and movable retainers K and H bevel at an inclination to the horizontal from the outer edges thereof upwardly towards the inner edges thereof, in order to 110 permit the swinging movement of the movable retainer H inwardly, into the room or building, and to prevent the swinging movement of the same in the opposite direction towards the outside of the window. This bevel arrangement of the abutting edges of the retainers H and K is best illustrated in 115 Figure 2 of the drawings at 60.

When the lower retainer H is in position in alignment with the fixed retainer K the parting beads or strip portions 40 and 51 130

thereof are in alignment with each other, and as are also the stop beads or constructions 41 and 52, to place the sash channels 42 and 53 in alignment for providing a track-
 5 way for receiving the lower window sash. In this position of parts it is to be noted that the upper end of the movable retainer H is anchored by the beveled construction of the abutting edges of the same and the fixed re-
 10 tainer K, to prevent the movement of the movable retainer H in any direction except at right angles to the plane of the sash inwardly towards the room. The lower end of the movable retainer K is anchored by the
 15 retaining shanks 55 and 56 against movement until the upper end of the retainer H is swung into the room and the shanks lifted out of place from their sockets in the casing sill and stool.
 20 In order to prevent the inward swinging or falling of the movable sash retainer H, it is preferred to provide some special catch means, and to this end a catch or detent 65 is provided, which includes a portion 67 countersunk in fixed relation from the outer surface of the stop bead 52, with an upper portion 68 hinged at 69 to swing outwardly away from the stop bead. The upper portion or leaf 68 of the detent 65 carries an
 25 arcuate retaining shank 70 preferably struck on a radius with the hinged axis 69 as a center, and this retaining shank 70 is adapted to enter an opening 71 formed transversely thru the retainer H, and as it is greater in length than the thickness of the retainer H, at its free end it is adapted to enter a socket 72 formed in the weight box or pulley stile, which receives the same and prevents the
 30 movement of the retainer H in any direction, until the leaf 68 is swung outwardly at right angles from its stop bead upon which mounted, to the position illustrated in Figure 4 of the drawings, and in which case the movable retainer H may then be swung
 35 into the room into the position illustrated in Figure 3, and the sashes are ready for detachment.
 40 As is illustrated in Figure 3 of the drawings, the movable sash retainers H upon releasing of the same by opening the detent 65 may be swung inwardly at their upper ends to the said position as illustrated, and the lower ends of the retainers H may be lifted upwardly and pivot on the sill structure of the window casing to support the lower sash at an inclination to the vertical, sloping into the room; the lower sash thus being entirely supported by the movable retainers H. The weight cord 25 may then be detached from the sashes and temporarily hooked to the casing jamb, and the lower sash may then be removed, as well as the movable retainers H. The upper sash C may then be lowered and removed by bodily moving the same inwardly towards the room; the

sash C in height being less than the distance from the sill to the lower edge of the rigid retainers K, to permit such detachment of the sash C, or swinging into a room to facilitate its handling.

The movable retainers H are attached to the window casing without nails or screws, and are readily detachable or movable with respect to the window casings, in order to permit access to the sashes, for inward swinging for cleansing purposes, or to facilitate the removal of the sashes.

In some instances it may be desirable to apply the principle of this invention to present window constructions, and to this end Figure 5 illustrates a modification of the movable retainer H; the movable retainer L of this view comprising a metal back piece 80, upon which the parting bead or strip 81 and the stop strip or bead 82 are connected in spaced relation to provide the sash channel 83. The stop beads 81 and 82 are otherwise formed exactly similar to the construction of the movable retainer H, as above described, and it is to be understood that the upper end of the retainer L is beveled the same as above described for the movable retainer H, and the beads 81 and 82 are stepped at their lower ends and respectively provided with attaching shanks 85 and 86, as above described for the retainer H.

From the foregoing description of this invention it is apparent that a novel type of window construction has been provided embodying an adjustment which will permit of the easy handling of the sashes, for the purposes of access, or to permit the removal of the same.

Various changes in the shape, size, and arrangement of parts may be made to the form of invention herein shown and described, without departing from the spirit of the invention or the scope of the claims.

I claim:

1. In a window construction the combination of a window casing including side stiles, a sash, retaining means for the sash including an upper fixed retainer for each of the side stiles and a lower movable retainer for each of the side stiles, each of the fixed and movable retainer of each side stile including spaced parting and stop beads providing a channel for receiving the sash therein, the lower edge of the fixed retainer and the upper edge of the movable retainer at each side stile, sloping from the inner side of the window casing downwardly towards the outer side of the window casing and being beveled from the side stile parallel with the plane of the window opening downwardly towards the window opening, and means for detachably holding the movable retainers in position below said beveled ends of the retainers including sockets formed in the lower portion of the window casing and project-

- ing spaced shanks carried at the lower end of the movable retainers for fitting in said sockets.
2. As an article of manufacture a retainer for sashes of window constructions comprising a body piece having rigid spaced parting and stop beads thereon to provide a sash receiving channel, the upper edge of said retainer being beveled transversely from front to back and from one side edge to the opposite side edge, retaining shanks projecting from the lower end of said retainer, and movable detent means carried by the retainer intermediate the ends thereof.
- 15 3. As an article of manufacture a retainer for sashes of window constructions comprising a body piece having rigid spaced parting and stop beads thereon to provide a sash receiving channel, the upper edge of said retainer being beveled transversely from front to back and from one side edge to the opposite side edge, retaining shanks projecting from the lower end of said retainer, and movable detent means carried by the retainer intermediate the ends thereof upon said stop bead and including a hinged leaf having a locking projection thereon, the retainer having a socket for receiving the locking projection therein.
- 30 4. As an article of manufacture a retainer for sashes of window constructions comprising a body piece having rigid spaced parting and stop beads thereon in spaced relation to provide a sash receiving channel, and retaining shanks projecting in spaced relation below the lower edge of the retainer in alignment with each of the parting and stop beads.
- 45 5. As an article of manufacture a detachable sash retainer for window constructions comprising a body piece having rigid spaced parting and stop beads in spaced parallel relation providing a sash receiving channel at the inner side of the retainer, said retainer at the lower ends thereof having the parting and stop beads disposed in an offset stepped relation, and reduced shanks projecting beyond the stepped ends of the parting and stop beads in alignment with said beads.
- 50 6. As an article of manufacture a detachable sash retainer for window constructions comprising a body having rigid spaced parting and stop beads thereon in spaced relation providing a channel therebetween for receiving a sash, the body having a socket disposed transversely therethrough at the stop bead, a member hinged at the outer side of the stop bead in spaced relation with respect to said socket opening, and an arcuate detent finger on said hinged member adapted to swing in the socket opening when the hinged member is moved towards the stop bead.
- 70 7. As an article of manufacture a detachable sash retainer for window constructions comprising a metallic supporting body having spaced parallel stop and parting beads at a side thereof to provide a sash receiving channel, means for detachably securing said retainer to a window construction including a detent movably carried by the stop bead for engaging a window casing, and spaced stepped retaining shanks extending below in alignment with the parting and stop beads.
- 75 8. In a window construction the combination of a window casing including side stiles and a sill construction including an inside stool and a base sill stepped below the inside stool, said inside stool and base sill at each of the side stiles having upwardly facing sockets therein in a spaced relation, a sash, and retaining means for the sash at each of the side stiles including an upper fixed retainer for each side stile and a lower movable retainer for each side stile, each of the fixed and movable retainers of each side stile including spaced parting and stop beads providing a channel for receiving the sash therein, the lower edge of the upper fixed retainer and the upper edge of the lower movable retainer at each side stile being formed to prevent transverse relative movement of the same, the lower ends of the movable retainer portions having the parting and stop beads disposed in an offset stepped relation, and having reduced shanks projecting in alignment with the beads for detachably seating in the sockets of said inside stool and base sill, and detent means carried by said movable retainers having means on the side stiles for engagement to hold the movable retainers in releasable positions.

GALELMA BUTCHER.
